UNITED STATES PATENT OFFICE.

CHARLES L. VAN DUNKER, OF SAN ANTONIO, TEXAS.

BASIN-PROTECTOR.

1,297,613.

Specification of Letters Patent. Patented Mar. 18, 1919.

Application filed January 23, 1917. Serial No. 144,022.

To all whom it may concern:

Be it known that I, CHARLES L. VAN DUNKER, a citizen of the United States, and resident of San Antonio, in the county of 5 Bexar and State of Texas, have invented certain new and useful Improvements in Basin-Protectors, of which the following is a specification.

This invention relates to an improved 10 sanitary temporary basin lining or protector.

The principal object of the invention is to provide a sanitary temporary basin lining or protector for use to line or cover the inner surface of basins or other forms of wash 15 bowls, commonly used in lavatories open to the public, especially those in use on railroad passenger coaches, steamboats and in hotels, whereby a person using the same will not be subjected to inconveniences and dangers 20 often encountered when washing in such places, caused by the frequent unsanitary condition of the basin or bowl.

Still further, the invention also aims to provide a basin lining or protector of the 25 character mentioned, which is provided with a suitable means for permitting the introduction therein of a projected water inlet, that is, that type of inlet as used in conjunction with certain types of lavatories now 30 marketed, which lavatories have for their water inlet, a projecting lip, whereby, to deflect the entrance of the water toward the bottom of the same, without doing material 35 injury to the basin lining or affecting the efficiency of the same in any way.

The improvements in the details and arrangement of parts will be apparent from an inspection of the accompanying drawings, in connection with the specific description 40 hereinafter contained and wherein the preferred embodiments of the invention are disclosed for the purpose of imparting a full understanding of the present improvements.

45 In the drawings:

Figure 1 is a perspective of the completed basin lining or protector.

Fig. 2 is a fragmental detail in top plan showing the form of discharge means, and

50 Fig. 3 is a fragmental sectional elevation of the same.

Referring more specifically to the drawings, wherein like reference characters designate corresponding parts in the several 55 views, my improved sanitary basin lining or protector is composed of a single sheet of

elliptical cut flexible material, such as heavy paper, card or pasteboard, the said sheet being so shaped as to constitute a basin lining, indicated by the numeral 1. In one side of 60 the basin lining 1 is formed a slit 2, the said slit extending parallel to the peripheral edge of the basin lining and providing for means whereby inlets in the bowl or like means may be introduced therethrough in order that the 65 basin lining may be filled with the cleansing fluid. Since the basin lining is formed with curved side portions, it is obvious, that means must be provided for whereby bulging or lapping of the same will be prevented 70 and to accomplish this end, I preferably, corrugate the said sides of the basin lining, the corrugations as shown in Fig. 1, being wider and deeper and in proximity of the top of the basin lining, but gradually decreasing in width and depth as they recede 75 or diverge toward the bottom thereof. By corrugating the sides, it is to be noted, that a dual object is attained, namely, the provision of properly formed side portions for 80 the bowl, and secondly, reinforcing of said side portions whereby to prevent collapsing of the same when packed for shipping and to permit expanding of the side portions when the lining is placed within a basin or other 85 form of wash bowl, thus permitting the lining to automatically adjust itself to the contour of the basin.

If desired, the basin linings may be formed without the slot 2, or they may during the forming or shaping thereof, be secured or otherwise weakened at this point, thereby permitting the user to readily break the same to permit the introduction of the water from the projection or opening in the 95 side of basins as used in lavatories of railroad passenger cars and other public places. Should the basin lining be made without the slit 2 or the scoring of that point as above described, the same is preferably formed 100 more shallow so that it may be readily seated within the basin or bowl and be of such height or depth as to not close or retard the free ingress of the water coming from the side of the basins having a source of supply 105 from the upper inside portions. For basins not having a water supply from the side, but wherein the supply is direct from the faucet or favelets above, the lining may be then made full depth in order to cover or 110 line the entire surface of the basin and without destroying any parts thereof.

It will be understood, that any suitable form of material may be used in forming the basin lining or protector, such as heavy oiled paper, waxed paper, including the conventional paraffined form, transparent parchment paper, and paste or straw board, or in fact any form of material which will serve to retain water for a temporary period of time as will permit the proper cleansing operation to be carried on. It is to be understood, that although I have stated in the above description that the lining is elliptically cut, the invention is not limited to this particular shape and further the ellipse or any other shape of material as used may be varied in size such as conditions or preference may dictate.

I provide means whereby the lining may be readily emptied when the cleansing operation has been completed by forming within the bottom of the bowl an opening, indicated by the numeral 7 and place thereover a suitable disk formed of material similar to that from which the bowl is formed, as indicated by the numeral 8, said disk having a tab 9 formed upon one side thereof, which tab is secured to a portion of the bowl bottom by some suitable water proof adhesive 10. Thus, to dis-

charge water or other fluid from the bowl, it is only necessary that the disk or flap valve 8 be removed from over the opening 7 whereupon, the said fluid will then be passed therefrom.

Instead of forming the basin lining of paper and the like material, rubber may be substituted therefor. A lining formed of a thin grade of rubber shaped as shown in the Fig. 1, either with or without the corrugations, as will be appreciated, will allow usage of the same for an extensive period of time.

Still further embodiments of the invention than those herein defined may be resorted to as conditions or preference may dictate, as may be in keeping with the hereto appended claim.

I claim:

A temporary lining for wash bowls comprising a body of flexible material adapted to conform to the inner surface of the bowl and having a drain opening in its bottom, said lining including an upwardly deflectable valve for said drain opening.

In testimony whereof, I affix my signature hereto.

CHARLES L. VAN DUNKER.
